UNITED STATES PATENT OFFICE.

EUGÈNE COLLON, OF CANNES, FRANCE.

MACHINE FOR FOLDING TABLE-NAPKINS OR OTHER FLAT LINEN ARTICLES.

SPECIFICATION forming part of Letters Patent No. 677,436, dated July 2, 1901.

Application filed February 2, 1900. Serial No. 3,703. (No model.)

To all whom it may concern:

Be it known that I, EUGÈNE COLLON, engineer, a citizen of the Republic of France, and a resident of 9 and 11 Rue de Cronstadt, Cannes, (Alpes-Maritimes,) France, have invented certain new and useful Improvements in Machines for Folding Table-Napkins or other Flat Linen Articles; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

The invention relates to improvements in machines for mechanically folding table-napkins, handkerchiefs, and like small goods, and has for its object mechanism for nipping, folding, creasing, and mechanically stacking the folded articles, and details of construction hereinafter fully described, and particularly pointed out in the claims.

Referring to the drawings, in which like parts are similarly designated, Figures 1 and 2 are diagrammatic views of end and side elevations of the principal devices in the machine. Fig. 3 is an end view of one of the feed-cylinders and the folding and creasing devices. Fig. 4 is a side view of the rope driving mechanism for the cams, and Fig. 5 is a section of the adjustable table for receiving the folded goods.

The napkin, handkerchief, or other article is laid out on the feeding-table *c*, Figs. 1 and 3, is taken by the cylinder *b*, which may or may not be covered with felt, as desired, and is nipped between this cylinder and a roller *a* just above it. This roller runs idle in bearings in the framing 20 and is close to but not touching the cylinder *b*, so that when the fabric is passed between said roller and cylinder the pressure drives the roller *a*. The shaft 3 of the roller *a* is supported in yielding bearings, said bearings held to their lower limit by a spring 21 at each end, whose tension can be varied by a screw and hand-wheel 22. The shaft 3 carries at its end a fast cone-pulley *h*, which drives, by means of a belt or cord 5, a second cone-pulley *g*, idle on the shaft 23 of the cylinder *b*. To this cone-pulley is connected the pulley 4, moving with

it, driving, by means of belt or cord 5^a, a pulley 6, loose on shaft 3. This pulley 6 is keyed or otherwise secured to the sleeve 2 on which 55 are secured two cams, which serve to operate the knives for folding the goods. Thus it will be seen that when no goods is passing between the roller *a* and cylinder *b* the former is stationary, the pulleys *g* and 4 run idle on 60 the shaft 23, and consequently the cams *y* and *z*, operating the knives, will also be stationary; but when a piece is passed between *a* and *b* the pressure between the two drives roller *a*, and the shaft 3, with its cone-pulley 65 *h*, which in turn drives *g* and 4 and the latter the pulley 6 and connected cams *y* and *z*.

The plates *d* and *j* or *d'* and *j'* are mounted on axles *o* and *p* in the framing and are so journaled or pivoted that these plates have 70 one end normally against or on the periphery of the cylinder *b*.

The folding-knives *e* *k* and *e'* *k'* may, as shown in Fig. 3, be carried by blocks *q* *r*, that are slidable in slots *s* *t* in the framing 20 to 75 and from the ends of the plates *d* *j*, that rest against the cylinder *b*, moving between said cylinder and plate and throwing the latter, which only rests against the cylinder *b* by its own weight, out from the cylinder. The knives 80 are moved by two armed levers *w* and *x*, pivoted at 24 and 25 to the framing, and whose ends are slotted at 26 and 27 to receive lugs 28 29 on the knives *e* *k* or on the blocks *q* *r*. The other ends of these levers are also slotted and receive lugs 30 31, that are secured to levers *u* *v*, operated by the cams *y* *z*, respectively.

Beyond each of the plates *d* *j*, spring-held against the cylinder *b*, are creasing-rollers *f* *l*, 90 whose pressure at each end is adjusted by means of a hand-wheel and screw 32 33, respectively.

Referring to Figs. 1 and 2, it will be seen that the goods is fed and folded in one direction, then falls on an endless belt *i*, and is carried to a second folding device, whose parts (indicated by the same letters with affixes) are similar in all respects to the first one and shown in detail in Fig. 3, with the exception 95 that the belt *i* forms the cover for the folding-cylinder *b'* and serves to make folds in the goods at right angles to those already formed. When completely folded and leav-

ing the endless belt *i* at the cylinder *b'*, the article slides across an inclined table 32 to the receptacle *m*. (Shown in section in Fig. 5.) This comprises a table *m*, variable in height, 5 and side boxes or members *n*, slideable to and from the table on the base 34. Each side member carries two fixed pulleys 35 and 36 at or near its top and a fixed pulley 37 near its bottom. In each side member there is 10 also a series of supports 38, each larger than the one next below, thereby forming shoulders 39, on which rest weights 7.

To the lower weight (the smallest in diameter) is connected one end of a cord or rope 15 40, which passes up through perforations in the center of the entire series of weights, over pulley 36 to lower pulley 37, and then over pulley 35 to one side of the table, where it is made fast.

20 The operation will be as follows: A napkin, handkerchief, or the like is fed from table *c* to roller *b*, carried under roller *a*, driving this roller and the cams *x* and *y* through the intermediate driving-belts 5 5^a. The goods 25 moves along the cylinder *b* and slides upon the plate *d* a certain distance, when the cam *y* lifts the lever *u*, which in turn lifts the end of lever *w* to depress the end carrying the knife *e*, which passes between the end of said 30 plate and cylinder *b* and throws up the plate *d* to fold the goods, which then passes under the creasing-roller *f*, the parts returning to normal position. Meanwhile another piece 35 of goods is fed from table *c* and the already-folded piece proceeds on its travel over the plate *j*. The second cam *z* now operates the lever *v* to operate the knife *k* in a manner similar to the operation of knife *e*. The piece 40 of goods is then creased by roller *l* and falls on the endless belt *i*, having two creases in it—that is, folded in three—and is carried by this belt to the second folding device to be similarly folded at right angles to the folds already made. From this second folding 45 device the articles drop on the inclined table 32, slide over it onto plate *m*, which by the increasing weight gradually sinks, lifting the smallest and lowermost weight 7 until it comes in contact with the weight next above 50 it, and when more articles fall on and weigh down the table both of these weights are lifted up to the next one, and so on, the table having a gradual downward movement counterbalanced by successively and automatically 55 added weights.

Having now described my invention, what I claim, and desire to secure by Letters Patent, is—

1. A machine for folding small goods, comprising a cylinder, a roller coöperating with said cylinder and driven by the pressure caused by passing the goods between the two, a device arranged to contact with the cylinder and lead the goods from the surface of the cylinder, a creasing-roller contacting with the cylinder beyond said device and a knife timed to fold said goods before it has entirely

left the cylinder over said device and move with it toward the creasing-roller, substantially as described. 70.

2. A machine for folding small goods, comprising a rotating cylinder, a roller coöperating therewith and driven by the pressure of goods between said roller and cylinder, plates for leading the goods off said cylinder at different points, folding-knives operated from said roller and organized to displace said plates and carry the goods toward yielding creasing-rolls, substantially as described. 75

3. A machine for folding small goods, comprising a rotating cylinder, a roller coöperating therewith, a device for stripping the goods from said cylinder, a creasing-roller contacting with the cylinder, a knife timed to crease said goods before being entirely stripped from the cylinder and to return it to the cylinder and under the creasing-roller, substantially as described. 80

4. A machine for the mechanical folding of flat pieces of linen, comprising the combination of a rotating cylinder and as many folding devices arranged around this cylinder as there are folds to be made in the same direction, each of these devices comprising a guide-plate supported at one edge against the cylinder in such a manner that it can be moved away therefrom, a knife having an intermittent to-and-fro movement arranged above the plate so as to press on the article to be folded in the angle formed between the plate and the cylinder and a pressing-roller arranged beneath the plate, the whole substantially as and for the purpose set forth. 90

5. A machine for the mechanical folding of flat pieces of linen, comprising the combination of a rotating cylinder, as many folding devices arranged around this cylinder as there are folds to be made in the same direction, each of these devices comprising a guide-plate supported at one edge against the cylinder in such a manner that it can be moved away therefrom, a knife having an intermittent movement arranged above the plate so as to press on the article to be folded in the angle formed between the plate and the cylinder, and a pressing-roller arranged beneath the plate, a roller mounted above the cylinder in such a manner that while it does not touch, it is sufficiently near said cylinder to be caused to rotate when the piece to be folded passes beneath and a mechanism for operating the knives by means of the roller, substantially as described. 105

6. A machine for the mechanical folding of flat pieces of linen, comprising the combination of a rotating cylinder, as many folding devices arranged around this cylinder as there are folds to be made in the same direction, each of these devices comprising a guide-plate supported at one edge against the cylinder in such a manner that it can be moved away therefrom, a knife having an intermittent to-and-fro movement arranged above the plate so as to press on the article to be folded in 110

- the angle formed between the plate and the cylinder and a pressing-roller arranged beneath the plate, a roller mounted above the cylinder in such a manner that while it does not touch, it is sufficiently near said cylinder to be caused to rotate when the piece to be folded passes beneath and a mechanism with a variable speed for operating the knives by means of the roller, substantially as described.
7. A machine for the mechanical folding of flat pieces of linen, comprising the combination of a rotating cylinder, as many folding devices arranged around this cylinder as there are folds to be made in the same direction, each of these devices comprising a guide-plate supported at one edge against the cylinder in such a manner that it can be moved away therefrom, a knife having an intermittent to-and-fro movement arranged above the plate so as to press on the article to be folded in 20 the angle formed between the plate and the cylinder and a pressing-roller arranged beneath the plate, a second rotating cylinder arranged at right angles to the first, as many folding devices similar to the first and arranged around the second cylinder as there are folds to be made at right angles to the first, and means for conducting the article to be folded from the first to the second cylinder, substantially as and for the purpose 25 30 set forth.
- In testimony that I claim the foregoing as my invention I have signed my name in presence of two subscribing witnesses.
- EUGÈNE COLLON.
